Filed Nov. 9, 1966, Ser. No. 593,178
3 Claims. (Cl. 89—33)

ABSTRACT OF THE DISCLOSURE

In abstract, this invention relates to an elongated, fixed restriction mounted in the ejection port of an automatic type shotgun to catch and retain shotgun shells as they are ejected through such port.

This invention relates to firearms and more particularly to means for engaging and retaining shotgun shell casings in the ejection port of automatic-type shotguns.

With the development over the last few years of improved casings for shotgun shells, particularly the various types of plastic shells now on the market, accompanied by the improved devices for reloading such shells, many hunters and a vast majority of trap and skeet shooters now reload and thus reuse their shells.

During contest shooting, however, the rules usually prohibit a shooter from retrieving his ejected shell casings from the ground. In certain types of competition such as trap shooting, the contestant is only allowed to fire one shell at the time. Devices to catch this shell as it is ejected from the gun have been attempted by the use of such things as bags, hoppers and the like. All of these devices, however, were large, cumbersome and distracting to the shooter at best.

After much thought and experimentation into the problems encountered and possible solutions thereto, applicant has devised a novel means of engaging and retaining the emptied shotgun shell as it is about to be ejected from the gun thereby allowing the shooter to retrieve the shell for reloading. The device at the same time does not in any way interfere or distract the contestant while firing his gun and does not in any way modify or change the balance of the gun, its weight or its shape. The device is also so constructed that it is easily attached to and removed from either the receiver or the barrel of an automatic shotgun, depending on the make and model to which it is being attached. Due to this feature of the invention, the device may be used during single shot competition and removed for other types of shooting.

It is, therefore, an object of the present invention to provide a means for engaging and retaining a discharged shotgun shell in the ejection port of an automatic shotgun so that such shell may be retrieved.

Another object of the present invention is to provide a resilient member mounted in the ejection port area of an automatic shotgun to engage and retain a fired shotgun shell as it is about to be ejected from such gun.

A further object of the present invention is to provide an elongated, shotgun ejection port restrictor with its ends bent in such a manner as to be received in openings adjacent the port.

Another object of the present invention is to provide a shotgun ejection port restrictor constructed of spring like, resilient material and adapted to engage either the receiver or barrel portion of the gun.

Other objects and advantages of the present invention will become apparent and obvious from a study of the following description and the accompanying drawings which are merely illustrative of the present invention.

In the drawings:

FIG. 1 is a side elevational view of the receiver por-

2

tion of a typical automatic shotgun showing applicant's restrictor mounted thereon;

FIG. 2 is a top plan view of such receiver portion disclosing the retained position in the ejection port of a fired shotgun shell;

FIG. 3 is an enlarged plan view of the restrictor member of the present invention; and

FIG. 4 is a cross section through lines 4—4 of FIG. 2.

With further reference to the drawings, FIG. 1 discloses the exterior portion and an automatic-type shotgun having a receiver 1, a stock 2, a barrel 3 and a fore-end 4. An operating handle 5 is provided in operative connection with breech bolt 6. A slot 7 is provided rearwardly of ejection port 8 and is so constructed to allow the operating handle 5 to pass thereto.

In the rear portion of the upper edge 9 of ejection port 8 are openings 10 and 10' which are preferably axially divergent in a plane parallel to the immediately adjacent exterior surface of receiver 1, particularly as disclosed in FIG. 4.

A restrictor member 11 is provided, preferably in the general shape disclosed in FIG. 3 (although similar shapes could obviously be provided without departing from the spirit of the present invention). As will be noted, the restrictor is an elongated member having each of its ends bent to lie in the same plane thereby forming a generally flattened U-shaped appearance. The end portions 12 and 12' of restrictor 11 are adapted to be placed in openings 10 and 10' of receiver 1. Restrictor 11 is preferably made of a spring-type of metal although any type of relatively hard material may be used. If a spring-type material is used in the manufacture of the restrictor, end portions 12 and 12' may be bent toward each other thereby allowing them to be inserted into openings 10 and 10' with the springing effect being used to retain such restrictor in its operative position as is obvious from a study of FIG. 1.

In actual operation of a gun incorporating the present invention, the shooter will pull trigger 13 thereby firing the gun which automatically forces the breech bolt 6 rearwardly to eject the fired shell casings 14 from the gun. Just as the shell is about to be thrown from the gun, the enlarged rim portion 15 thereof will come in contractive gripped engagement between restrictor 11 and the lower edge 16 of ejection port 8. Since the rim is too large to pass between the two obstructions, the shell will be retained in the ejection port until it is manually removed by the shooter, thereby saving it to be reloaded and reused as desired.

If the barrel of the gun extends rearwardly in the area of the ejection port, as in the Model 1100 Remington automatic shotgun and similar types, the restrictor may be attached to this barrel rather than the receiver. Certain other automatic-type shotguns have features such as the barrel moving rearwardly rather than the breech bolt. This type of gun may be easily adapted to use the present invention by using openings in the receiver since the barrel could not be obstructed. The operation of either gun, incorporating the modification of applicant's invention, would be substantially the same.

It is obvious from the foregoing that the present invention has the advantage of providing a simple, inexpensive means for receiving and retaining used shotgun shells so that the same may readily be retrieved for reloading or other purposes without materially modifying or changing the various handling characteristics and general feel of the firearm.

The terms "upper," "lower," "rear" and so forth have been used herein merely for convenience in the foregoing specification to describe the firearm and ejection port restrictor as oriented in the drawings. It is to be understood, however, that these terms are in no way limiting

to the invention since the firearm may obviously be disposed in many different positions when in use.

The present invention may, of course, be carried out in other specific ways than those herein set forth without departing from the spirit and the essential characteristics of the invention. The present embodiments are, therefore, to be considered in all respects as illustrative and not restrictive and all changes coming within the meaning and equivalency range of the appended claims are intended to be embraced therein.

What is claimed is:

1. In an automatic-type shotgun having a receiver and an ejection port defined by upper, lower, forward and rear edges in one side of said receiver, the improvement comprising: a pair of openings in the rear portion of the upper edge of said port, the alignment of said openings being axially divergent from interior to exterior in a plane generally parallel to the exterior portion of said receiver; and fixed restrictor means within said ejection port having end portions placed in said openings whereby the height of said ejection port is decreased to engage and retain shell casings passing through said ejection port. 15

2. The device of claim 1 wherein the restrictor means comprises an elongated member having its end portions bent in a plane, the accumulative total of whose angles 20

equal the angle of divergence between the axially divergent openings.

3. In an automatic type shotgun having a receiver and an ejection port defined by upper, lower, forward and rear edges in one side of such receiver, the improvement comprising: a pair of openings in the rear portion of the upper edge of said port, the alignment of such openings being axially divergent from interior to exterior in a plane generally parallel to the exterior portion of said receiver; and an elongated restrictor member having end portions placed in said openings, said end portions being bent in a plane, the cumulative total of whose angles equals the angle of divergence between the axially divergent openings whereby the height of said ejection port is decreased to engage and retain shell casings passing through said ejection port. 10
